JAMES HOPKINS ADAMS, OF KENSINGTON, MARYLAND.

BED FOR PLAYING-TABLES.

1,259,951.

Specification of Letters Patent. Patented Mar. 19, 1918.

Application filed August 17, 1914. Serial No. 857,186.

To all whom it may concern:

Be it known that I, JAMES H. ADAMS, citizen of the United States, residing at Kensington, in the county of Montgomery and State of Maryland, have invented certain new and useful Improvements in Beds for Playing-Tables, of which the following is a specification, reference being had therein to the accompanying drawing.

10 This invention relates to an improved bed for playing tables, and more particularly to that class of playing tables wherein a smooth, hard, even surface is required and over which balls or projectiles are played.

15 Heretofore in the art of table beds of this character it has been usual to form them of slate slabs, and while it has been suggested in numerous instances heretofore to form these beds of cement or cement compositions

20 and to provide such structures with reinforcements, as far as I have been able to ascertain a satisfactory composition bed has not heretofore been produced.

An essential in a bed for playing tables 25 is that of smoothness and hardness so that its surface will not be endangered upon the dropping of the ball or other object thereon, a close union of joints, and a maintenance of the perfectly level accurate playing surface.

The object of my present invention is the production of a composition bed for playing tables which will possess the characteristics of strength and rigidity, substantially 35 perfect in the maintenance of the proper level playing surface, easily associated, cheaply produced as compared with the usual form of table surfaces and one wherein in the general construction of the supporting

40 frame or frame work the major portion of the usual fabricated structure may be dispensed with.

I have, in the accompanying drawings, shown an embodiment of the invention and 45 have as heretofore stated referred to the invention as being one designed for a table playing bed. It is to be understood, however, that the invention can be employed with great satisfaction in the art of playing boards and also in other analogous arts.

I also wish it understood that the invention is not necessarily limited to all the details and special arrangements shown and described as modifications and changes in 55 the arrangement of parts can be made without departing from the nature and principle

of the invention and which may come well within the range of mechanical equivalents of the features shown.

For convenience I have illustrated the invention as applicable to a billiard table surface and have shown the bed disassociated from the supporting legs or frame. It is to be understood that any convenient design or form of supporting frame may be employed.

In the drawings:

Figure 1 is a plan view of the bed showing the surrounding frame in its finally adjusted position;

Fig. 2 is a longitudinal section;

Fig. 3 is an enlarged detail sectional view showing parts broken away;

Fig. 4 is a horizontal section through one of the joint portions of the bed, and

Fig. 5 is a detail section of a modification.

In the production of the table bed a convenient method of procedure is that of forming the bed in section, although the present invention is not necessarily limited in certain aspects to a sectional bed.

In Fig. 1 the sections A, B and C are represented as being surrounded by the framework D. For the purposes of this specification, the section A will be referred to, it being understood that the other sections are substantially the same in their general construction. In building up and forming the sections a suitable mold is employed having conveniently a plate glass bottom. Upon this perfectly smooth surface I place a composite cementitious material *a* which is conveniently formed of one-third fine, well-cleansed sand, one-third high grade Portland cement and one-third plaster of Paris or its equivalent. This material is then mixed with a proper amount of fluid and in that particular I have found that to render the surface nonhygroscopic a certain amount of mineral oil or saponaceous material may be mixed with the fluid to form an emulsion and the cement or composition thoroughly impregnated or mixed therewith. This material after being placed in the mold on the smooth glass base will when set, constitute a perfectly smooth, hard, fine non-hygroscopic surface for the table bed.

The slab is then built up by adding thereto the ordinary cement composition *a'* until the required thickness, conveniently two to two and one-half inches, more or less, is secured. During the formation of the slab and to add

rigidity to the upper face thereof, a wire mesh a^3 is embedded in the material. The slab is formed at its inner edge with an overlapping top part A' for purposes presently to be described. The outer edges of the slab are, during the process of molding, formed with a rabbet, as at a^4 , the same entering a short distance below the top of the slab for purposes presently to be stated.

10 The center slab B is made substantially the same as the outer slab A, with the exception that the rabbet a^4 is formed at the ends only and the overlapping portions A' are made respectively on the top portion at one edge and the bottom portion, as at A² on the other edge, as shown in Fig. 2. The three slabs A, B and C, after being constructed in accordance with the method of procedure referred to in the description of the formation of the slab A are assembled, as shown in Fig. 2, with adjacent parts or projecting portions overlapping. This is important inasmuch as the joints are by this means supported and held in proper relative position.

15 25 To support the slabs in the frame D and to lock the same in close relation with each other, as well as to give reinforced strength to the cement I conveniently extend through each slab, tubes E, the same extending crosswise laterally and longitudinally. The lateral tubes E' are so positioned in the cement that the upper longitudinal tubes will rest thereagainst, thereby forming when in position, a very rigid reinforcement the entire reaches of which when the bed is assembled will find support by the shorter reinforced tubes E' as clearly shown in Fig. 3. These tubes terminate at the edges of the slab and for supporting and uniting purposes cylindrical bars F are extended through the tubes, their ends projecting through the side frame members D and are there threaded to receive nuts F' which are conveniently positioned in countersunk recesses f of the surrounding frame. The parts being properly assembled, the slabs are tightly drawn together by tightening the nuts on the supporting bars F, and owing to the fact that the supporting bars are extended into the surrounding frame the entire bed structure is thus built up, the slabs being supported by the reinforcing supporting bars and their associated tubes and a substantially perfect playing surface is thus presented. It has been ascertained that a table bed built in accordance with the above description will be highly satisfactory, but as a precaution against the chipping or breaking of the edges or corners of the upper portion of the cement surface, a metal curbing or edging G may be employed. This metal curbing or edge protector is conveniently a strip of steel or other suitable metal which is embedded in the edge

60 65 of the cement slab having anchoring points

g, g' embedded in the body of the slab, as shown in Fig. 4.

I desire it understood that any convenient form of anchorage may be employed, but the one shown is sufficient to indicate the general way of securing the metal strips in place. It will be observed that these metal protecting strips are extended around the corners and that if found desirable this feature may be carried into other parts of the slabs, thus protecting the edges of the playing surface should the slabs be transported or shipped.

The two protecting metal strips G are so finished that their upper edges come in direct surface alignment with the playing surface of the table bed, thus forming in fact a continuity of the playing surface.

It has also been found convenient to place a reinforcing bar H in the projecting lower overlapping portion of the slabs, as shown in Figs. 2 and 3. In some tables, however, this may be omitted.

In Fig. 2 of the drawings the reinforcing supporting and clamping rods F are shown and used without the employment of the metal tubes E. An advantage of the metal tube arrangement is that in drawing the supporting rods in or out, there is no tendency to enlarge the rod receiving passage or hole in the cement and the table is thereby accurately adjusted. It has been found convenient in finishing the table bed to form the rabbets a^4 so that the felt or other covering J can be properly stretched over the surface.

The cloth is first stretched tightly and the securing strip K is then inserted in the rabbet, thus binding tightly the cloth between the frame and the shouldered part of the slabs. It has, however, been found convenient to provide means for retaining these strips K in place and with that in view there has been provided a series of points or projections k conveniently in the form of small nails or tacks passing through the strips with their points projecting outward. While in this position with the strips properly positioned in the rabbets of the slabs the frames are drawn down tight and the pins enter the frame forming securing means for the strips, thus maintaining the parts in position.

As a playing bed, the construction comprising the surrounding frame represents a unitary structure and onto this may be built up the finish of a table, including proper decorative side parts and supporting leg structures, the proportions of the surrounding frame being sufficient to constitute the frame onto which the substructures or supporting features are secured.

Of course it is to be understood that a substructure may be employed having cross braces but the present unitary playing bed,

as shown in the drawings and described, is in itself capable of constituting the entire framework around which the substructure is built and that owing to the suspension of the slabs on the reinforcing binding and supporting bars it is not necessary to have a supporting frame-work below the slabs. This will do away with material weight to the table as a whole and the playing bed 10 may be employed without the necessity of a substructure as many of the so-called wooden bed billiard and pool tables are now used.

In forming the slabs it has been found 15 convenient to foreshorten slightly the lower tongue at the edge of the slab, as shown in Fig. 3, so that during the clamping operation of the parts of the bed, there will be an assurance of a close contact between the 20 upper portions of the bed. It may be here remarked that the wire mesh may be omitted, if desired, and further, that the general characteristic of the supporting of the bed itself by the clamping and supporting bars 25 F may be embodied in a single or a two part structure. It is to be understood also that the cover securing strip may be glued in place or otherwise secured, if desired.

When desired the bed may be provided 30 with a playing surface on both of its sides as shown in Fig. 5 of the drawings wherein the lower surface of the bed, as indicated at L, is formed the same as the upper surface shown in the other figures. The construction is otherwise made the same. This arrangement will enable the user to turn 35 the bed over when desired or the manufacturer to so fashion the bed so that other games than that of billiard or pool may be 40 played thereon. In forming the under surface into a playing surface the plate glass preferably employed is pressed forcibly onto the finished strata or coating of cement and by this pressure an even playing surface is 45 produced.

Having thus described the invention, what is new and desired to be secured by Letters Patent is:

1. A bed for game playing devices comprising a cement structure having a non-hygroscopic smooth surface part. 50 2. A bed for playing devices comprising a cement body part having a fine composite surface portion having a moisture repellent 55 characteristic.

3. In a playing table surface, the combination with a frame, of a series of composition slabs, means for uniting the slabs and interposed metallic strips between the 60 edges of the slabs at the upper surface thereof.

4. In a playing table surface, the combination with a frame, of a series of composition slabs, means for uniting the slabs and interposed metallic strips between the 65

edges of the slabs at the upper surface thereof, said strips extending around the corners of the slabs.

5. In a playing table surface, the combination with a supporting frame, of a bed 70 comprising a series of composition slabs, each having a series of tubular reinforcements therein, a surrounding frame, and bars passing through the tubular reinforcements and anchored in said surrounding 75 frame.

6. In a playing table bed, the combination with a slab member having a tubular reinforcement extending thereacross, a similar tubular reinforcement extending at an 80 angle thereto and immediately below said other tubular reinforcement, and supporting bars passing through the tubes.

7. In a bed for playing tables, the combination with a series of composition slabs, 85 each having aligned tubular reinforcements arranged at an angle to each other and in contact at their crossings, substantially as described.

8. In a bed for playing devices, the combination with a surrounding frame, of a plurality of slabs, of hollow reinforcing rods arranged in said slabs and uniting and supporting bars passing through the hollow reinforcing rods. 90

9. In a bed for playing tables, the combination with a playing surface, comprising a series of slabs having their adjacent ends overlapping, and reinforcing rods arranged 95 in the overlapping ends.

10. A table bed comprising a slab member having a rabbet around its upper edge, a metallic reinforce arranged on the slab edges, a frame member and a cover securing strip for the rabbet member. 100

11. In a playing table surface, the combination with a supporting frame, of a bed comprising a series of composition slabs having their adjacent ends overlapping, of transverse reinforcing rods arranged in the 110 overlapping ends, of a tubular reinforcement arranged in each slab, extending thereacross, a similar tubular reinforcement extending at an angle thereto and immediately below said other tubular reinforcement and 115 a supporting bar passing through the tubes.

12. In a playing table, the combination with a slab member having a rabbet at its upper edge, a frame member and a cover securing strip for the rabbet member. 120

13. In a playing table, the combination with a composite slab member having a rabbet at its upper edge, a frame member and a cover securing strip for the rabbet member.

14. A bed for playing tables comprising 125 a slab member having a hollow reinforcing rod arranged therein and a supporting and engaging rod passing through the hollow reinforcing rod.

15. A bed for playing tables comprising 130

4
a slab member having hollow reinforcing rods extending longitudinally and transversely therethrough and supporting and connecting rods passing through said hollow reinforcing rods.

5 16. In a playing table surface, the combination with a frame, of a series of slabs constituting the surface, means for uniting the slabs, and protecting means between the edges of said slabs, substantially as described.

10 17. In a playing table surface, the combination with a frame, of a series of composition slabs constituting said surface disposed within the frame, means for uniting said slabs and protecting devices interposed between the edges of the slabs at the upper surface thereof, for the purpose described.

15 18. In a playing table surface, the combination with a frame, of a surface composed of separable members, and interposed protecting devices located between the edges

of said separable members when the same are in an assembled position for the purpose described.

25

19. In a playing table surface, the combination with a frame, of a plurality of composition slabs, and means passing through said slabs for securing the same together.

30

20. In a playing table surface, the combination with a frame, of a plurality of sections supported by said frame, and means for maintaining said sections together and to the frame comprising a plurality of metallic devices passing through the sections and engaging the frame, substantially as described.

35

In testimony whereof I hereunto affix my signature in the presence of two witnesses.

JAMES HOPKINS ADAMS.
